UNITED STATES PATENT OFFICE.

HENRY SCHRÖDER, OF CHICAGO, ILLINOIS.

AEROPLANE.

1,382,861.

Specification of Letters Patent. Patented June 28, 1921.

Application filed May 19, 1919. Serial No. 297,984.

To all whom it may concern:

Be it known that I, HENRY SCHRÖDER, a former subject of the Emperor of Germany, who have declared my intention of becoming a citizen of the United States, and a resident of the city of Chicago, county of Cook and State of Illinois, have invented certain new and useful Improvements in Aeroplanes, of which the following is a specification.

My invention relates to improvements in aeroplanes and has for its object the provision of an improved construction of this character provided with improved means for operating and manipulating the same, greatly facilitating the commencement of flights and landing after a flight.

Other objects will appear hereinafter.

The invention consists in the combination and arrangements of parts hereinafter described and claimed.

The invention will be best understood by reference to the accompanying drawings forming a part of this specification, and in which,

Figure 1, is a top plane view of an aeroplane embodying the invention and shown in position of flight;

Fig. 2, an enlarged detailed view of the engine and associated parts shown in position assumed in the commencement of a flight;

Fig. 3, an enlarged side view of the aeroplane shown in position for the commencement of flight, and

Fig. 4, a front view corresponding with Fig. 3.

The preferred form of construction as illustrated in the drawings comprises a suitable frame 5 having the usual vertical plane 6 mounted in the tail or rearward portion thereof, said frame 5 being mounted to run upon runners 7 and 8, as indicated.

The main supporting planes of the aeroplane are in the form of sections 9, each of said sections being pivotally mounted as indicated to normally hang vertically when the plane is at rest or is in the act of ascending or descending, but automatically swinging rearwardly into substantially horizontal positions when forward motion is imparted to the aeroplane, as will be readily understood, the resistance to the air causing such rearward swinging of the plane sections 9, and the frame being arranged to engage and limit such rearward swing when substan-

tially horizontal positions have been assumed. The form of aeroplane illustrated is the ordinary bi-plane construction and two rotation-preventing plane sections 10 are associated with the upper set of supporting planes 9. These rotation-preventing planes 10 are secured to a transverse shaft 11 at slight angles to each other as shown, so that when the aeroplane is ascending said plane sections 10 will assume the positions shown in full lines in Fig. 3, but when the aeroplane is traveling forwardly, said plane sections will assume the positions indicated in dotted lines in Fig. 3. The shaft 11 carries two beveled gears 12 meshing with beveled gears 13 at the upper ends of shafts 14 having beveled gears 15 at their lower ends meshing with beveled gears 16 on a transverse shaft 17 upon which the engine 18 is mounted to oscillate. Engine 18 is equipped with the usual propeller shaft 18' carrying the usual propeller 18'' at its free or swinging end as shown. The trunnion shaft 17 carries a rocker arm 19 connected by a link 20 with an adjusting lever 21 co-operating with a notched segment 22 and by means of which the engine may be swung so as to bring the propeller shaft 18' either into horizontal or vertical position as indicated. The tail of the machine is equipped with a horizontal tail plane 23 mounted to swing into either horizontal or vertical position as shown. The cable 24 is attached at one end to an eye 24' on the plane 23 and leads thence over suitable guide pulleys on the frame 5 and over the guide pulleys 25 and 26, respectively, which are mounted on the engine frame, the other end of the cable 24 being secured to the free end of the rocker arm 95 attached to the plane 23.

In use, when it is desired to commence a flight, the operator adjusts the engine to cause the propeller shaft 18' to project vertically as shown in Fig. 3. When in this position, the planes 9, 10 and 23 will assume the positions indicated in full lines in Fig. 3. Then the engine is started and the thrust of the propeller 18'' being directly upwardly the aeroplane will be lifted off of the ground bodily, the vertical positions of the planes 9 and 23 permitting of such free vertical movement of the aeroplane, and planes 10 tending to prevent rotation of the aeroplane under the influence of the reaction from the propeller 18''. When a suitable elevation has been reached, the operator by manipu-

2
lating the lever 21 adjusts the propeller shaft and engine until the propeller shaft extends substantially horizontally, whereupon the thrust of the propeller will be forward. This adjustment of the engine 5 adjusts the planes 10 into the dotted line position shown in Fig. 3 and the plane 23 into its horizontal position, which are the correct positions of these planes for forward flight, 10 planes 10 again serving to prevent rotation of the aeroplane under the reaction from the propeller 18'. Upon forward movement of the aeroplane, the plane sections 9 automatically swing rearwardly and upwardly into 15 substantially horizontal positions, whereupon they serve the usual functions of the supporting planes of an aeroplane. In alighting, the operator may alight in the usual way or may adjust the propeller shaft again 20 into vertical position and operate the same at a speed somewhat less than the elevating speed, but sufficient to prevent falling of the aeroplane and permitting of gentle settling of the same on to the earth, but in a substantially 25 vertical direction.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 35 appended claims.

Having described my invention what I claim as new and desire to secure by Letters Patent is:—

1. An aeroplane comprising a frame; 40 planes thereon adjustable into different positions relatively to the vertical; an angularly adjustable propeller on said frame; an operative connection between said planes and said propeller for adjusting said planes upon adjustment of said propeller; supporting planes pivotally mounted on said frame on an axis arranged transversely with reference to the direction of travel thereof, said supporting planes being arranged to hang 45 normally in substantially vertical positions; and means for limiting the rearward swing of said supporting planes, substantially at horizontal positions, substantially as described.
- 50 2. An aeroplane comprising a frame; main supporting planes pivotally mounted on said frame to hang normally in vertical positions; means for limiting the rearward swing

of said planes, substantially at horizontal positions; pivotally mounted rotation preventing planes associated with said main supporting planes; means for adjusting said rotation preventing planes to different angular positions; an angularly adjustable propeller on said frame; and an operative 60 connection between said rotation preventing planes and said propeller for adjusting said planes upon adjustment of said propeller, substantially as described.

3. An aeroplane comprising a frame; main 70 supporting planes pivotally mounted on said frame to hang normally in vertical positions; means for limiting the rearward swing of said planes substantially at horizontal positions; pivotally mounted rotation 75 preventing planes associated with said main supporting planes; means for adjusting said rotation preventing planes to different angular positions; an engine in said frame; a propeller shaft and propeller carried by said 80 engine; means for swinging said engine, propeller shaft, and propeller from horizontal into vertical position and vice versa; and an operative connection between said engine and said rotation preventing planes for adjusting said planes upon adjustment of said engine, substantially as described.

4. An aeroplane comprising a frame; main 85 supporting planes pivotally mounted on said frame to normally hang vertically; means 90 for limiting rearward swing of said planes substantially at horizontal positions; pivotally mounted rotation-preventing planes associated with said main supporting planes; means for adjusting said rotation-preventing planes to different angular positions; a tail supporting plane mounted at the rear 95 of said frame and pivoted to swing into horizontal or vertical position; an engine in said frame; a propeller shaft and propeller carried by said engine; means for swinging said engine, propeller shaft and propeller from horizontal 100 into vertical position and vice versa; and an operative connection between said engine and said rotation-preventing and 105 tail planes for adjusting said planes upon adjustment of said engine, substantially as described.

In testimony whereof I have signed my name to this specification in the presence of 110 two subscribing witnesses.

HENRY SCHRÖDER.
